BROADCASTING STUDIO

Joseph K. Gannett, Montclair, N. J., and Robert Smith, Jr., Richmond Heights, and Brown W. Saveland, Cleveland Heights, Ohio, assignors to The Austin Company, Cleveland, Ohio, a corporation of Ohio

Application November 12, 1943, Serial No. 509,996

7 Claims. (Cl. 20—1.12)

1

This invention relates to buildings and, as one of its objects, aims to provide a building of an improved design and construction rendering the same especially suitable for use as a broadcasting studio or the like and for the presentation of exhibits of all kinds.

Another object of this invention is to provide a building of this kind, having a plurality of observation or seating rooms served by a rotatable stage and by a single control and broadcasting station, so that a desired continuity or succession of programs can be maintained and a duplication of costly broadcasting and television apparatus can be avoided.

A further object of this invention is to provide a building of the kind mentioned, in which the observation rooms and the control station or room occupy novel positions relative to the stage.

Still another object of the invention is to provide a building of this kind having a rotatable stage, and in which the observation rooms, the common control room and certain auxiliary rooms occupy novel positions relative to the stage.

The invention may be further briefly summarized as consisting in certain novel combinations and arrangements hereinafter described and particularly set out in the appended claims.

In the accompanying sheets of drawings:

Fig. 1 is a plan view of the mezzanine floor of a building or studio embodying our invention.

Fig. 2 is a partial plan view of the first floor, and

Fig. 3 is a partial sectional elevation view taken through the building substantially on line 3—3 of Fig. 2.

As already indicated in a general way, our novel building 10 can be used for exhibits of all kinds but is especially suitable for use as a studio in which artistic or theatrical programs can be presented in connection with radio and television broadcasting or for various other purposes. As shown in the drawings, the building has a walled portion or enclosure 11 housing a rotatable stage 12 and an adjacent walled portion 13 containing various rooms including a pair of main observation or seating rooms 14 and 15. The building section 11, which constitutes the rearward portion of the building, can be of any desired shape and in the present embodiment of the invention is substantially circular with an annular space 16 extending between the outside wall 11a and the periphery of the rotatable stage or turntable 12. The building section 13 forms the front portion of the building and is of an appropriate shape and height to house the observation rooms 14 and 15

and to provide a central projection 17 containing a suitable entry 18 and a lobby or foyer 19.

The rotatable stage 12 comprises a substantially circular floor or turntable which is rotatable about a central post or axis 21 and a plurality of intersecting upright walls 22 and 23, which divide the stage into a number of display areas or sets. In this instance the walls 22 and 23 intersect each other at substantially right angles and define four display areas or sets designated A, B, C and D.

In the drawings the display area or set A is shown as being in a viewing position, that is to say it is in the position or station in which the performance or exhibit being presented in this set is visible from the observation rooms 14 and 15. The upright walls 22 and 23 may be of any desired height which will render the display areas suitable for the purpose intended and, as shown in Fig. 2, these walls may be provided with passages or doorways 24 connecting the adjacent display areas with each other and through which the actors or artists appearing on the stage can enter or leave the set A. The scenery for the set A can be located at different desired positions, depending upon the character of the performance or exhibit being presented, and in Fig. 2 the broken lines 24a and 24b represent two such positions.

As mentioned above, the set A is shown as being in the viewing position in which the performance or exhibit being presented in this area can be observed from one or both of the rooms 14 and 15. The other sets B, C and D are out of sight of the audience which may be present in the observation rooms 14 and 15 and while these areas or sets are in this position, the stage settings can be erected or prepared therein without being seen from the observation rooms. After the exhibit or performance of set A has been presented or completed, the stage 12 is rotated to bring another of the sets or display areas into the viewing position. The portion 16a of the annular space 16, which lies outside of the observation rooms 14 and 15 and extends between the stage 12 and the outer wall 11a, can be used as a workshop or as a storage space for scenery and from which space workmen can enter the display areas B, C and D for preparation of the stage settings therein.

The observation rooms 14 and 15 are located so that they face the set A and extend rearwardly away from the stage in diverging relation. Each observation room contains rows or tiers 25 of seats for the observers or audience. The inner or

lower ends of these observation rooms have a relatively low or partial front wall 26 and a front opening 27 above such wall and through which the set A can be seen by the audience. The seat rows or tiers 25 extend upwardly and rearwardly from the front wall 26 to a passage 28 which extends across the rear or upper end of each observation room and is connected with the mezzanine floor 29. Stairways or aisles 30 located on opposite sides of the central seating are of the observation rooms lead forwardly and downwardly from the passage 28 and afford access to the various rows of seats.

The diverging relation of the observation rooms 14 and 15 is preferably such that these rooms extend substantially at right angles to each other with portions 31a of their outer or remote side walls 31 extending over the rotatable stage 12 in substantially aligned relation with the upright intersecting walls 22 and 23 of the stage. This registering relation between the side walls 31 of the observation rooms and the upright walls 22 and 23 of the set A limits the vision of the audience to the set or area occupying the viewing position and conceals the entire backstage area from the view of the audience. Doorways 32 are provided in the walls 31 adjacent the point of register with the upright walls 22 and 23 of the rotatable stage and afford passage to the backstage areas from the space 16b lying between the rotatable stage and the adjacent ends of the observation rooms 14 and 15. As shown in Fig. 1 the front opening 27 of each of the main observation rooms 14 and 15 is provided with a suitable curtain 33 which can be lowered or drawn to a closed position for cutting off the set A from the vision of the audience. The curtain for the observation room 14 can be opened and closed independently of the actuation of the curtain for the room 15.

Another feature of the present invention is the provision of a control room or station 35 between the inner or adjacent ends of the observation rooms 14 and 15, such inner ends being spaced apart to permit the set A to be seen from the control room. This control room may be used as a central station for directing the performance or exhibit being presented in the set A and for operating or controlling radio broadcasting and television equipment which may be used in connection with the performance or exhibit being presented. The control room or station can also be used in supplying or controlling the music or illumination for the performance or exhibit and as the station from which the curtains 33 are actuated and from which instructions or explanations can be given to the audience in the rooms 14 and 15 by suitable sound or visual signalling means.

As shown in the drawing the control room or station 35 includes a lower floor or room 35a in which the broadcasting and television apparatus and various other equipment may be located. The equipment room 35a is connected with the control room 35 thereabove by the circular stairway 36. A portion or section 37 of the front wall of the control room 35 is transparent and is located to afford direct vision of the set A from such control room. The location of the transparent section 37 is also such that the persons seated in the observation rooms 14 and 15 can not readily see into the control room and will therefore not have their attention diverted from the performance or exhibit. The rear wall of the control room also contains a transparent section

38 through which the interior of the control room can be seen from the mezzanine floor 29, as indicated in Fig. 3. The side walls of the observation rooms 14 and 15 are opaque as is usual in buildings of this character and, as shown in Fig. 1, portions of the inner or adjacent side walls of the observation rooms form the side walls of the control room 35.

By locating the control room 35 and the equipment room 35a between the main observation rooms 14 and 15 and in proximity to the set A, as above explained, these rooms and the equipment therein can be used to serve both observation rooms thereby avoiding duplication of such equipment which is of a very costly nature. The observation rooms 14 and 15 can, if desired, be filled simultaneously so that an audience in each room will see the set A at the same time. Preferably, however, the observation rooms 14 and 15 are filled and emptied alternately in succession so as to permit the programs and the use of the above-mentioned expensive equipment to be carried out in a substantially continuous manner. In other words one of the observation rooms, for example the room 14, can be filled and its curtain 33 withdrawn to permit the set A to be observed by such audience. During this performance the room 15 can be filled while the curtain 33 is in its drawn or closed position. At the completion of the performance or program in set A the curtain for the observation room 14 is closed and the stage 12 is rotated to bring another set into the viewing position whereupon the curtain of the observation room 15 is opened. While the new set is being observed by the audience in the room 15, the room 14 can be emptied and refilled with a new audience and this procedure can be repeated indefinitely.

Another feature of the present invention is the utilization of the space on the first floor of the building and beneath the observation rooms 14 and 15 in a novel manner. As shown in Fig. 2, a pair of dressing rooms 39 and 40 is located beneath each main observation room adjacent the inner end thereof. Various other rooms are located beneath the observation rooms such as the offices 41 and 42, and a utility room 43 for heating and air conditioning equipment. Between each pair of dressing rooms 39 and 40 a special observation room 44 is provided which may be occupied by a representative of the person or company sponsoring the broadcast or performance being presented on the stage. These special observation rooms 44 have a transparent front wall or window 45 located in the wall 26 and through which the set A of the stage can be directly observed. Other rooms 48 and 49 located adjacent the equipment room 35a may contain cameras, projectors and various other necessary apparatus. By locating a pair of the dressing rooms 39 and 40 and one of the special observation rooms 44 beneath each of the main observation rooms, it will be seen that the dressing rooms and special observation rooms will be in close proximity to the stage 12 and that these groups of rooms can be entered and vacated alternately by the personnel associated with the successive programs and hence, delays and confusion will be substantially eliminated.

Reverting to the description of the front projection 17 of the building, it will be seen in the drawings that stairways 50 are provided which connect the mezzanine floor 29 with the lobby 19. At a suitable point in the lobby an information desk or ticket office 51 may be provided.

From the foregoing description and the accompanying drawings it will now be readily seen that we have provided a novel form of building or studio which can be used for exhibits or performances of all kinds and is especially suitable for radio and television broadcasting purposes. It will be seen also that the provision of a rotatable stage and a plurality of observation rooms permits a continuous succession of programs to be presented without interruption. Likewise, it will be observed that with the present arrangement the observation rooms and stage are served by one control room and one set of equipment and that the latter can be used continuously during the successive exhibits or programs. Furthermore, it will be seen that the compact arrangement provided in our novel building permits a group of utility rooms to be located beneath each of the main observation rooms and in close proximity to the rotatable stage.

While we have illustrated and described our novel building or broadcasting studio in considerable detail, it will be understood, of course, that we do not wish to be correspondingly limited but regard our invention as including all changes and modifications coming within the spirit of the invention and the scope of the appended claims.

Having thus described our invention, we claim:

1. In a building of the character described, a stage having a substantially circular floor and upright walls dividing the same substantially into quadrants, said stage being rotatable for moving one of said quadrants to a viewing position, and a pair of observation rooms facing said viewing position and extending in diverging relation away from the stage, said observation rooms having front openings directed toward said viewing position and the latter being common to both rooms, the outer side walls of said observation rooms extending at substantially right angles to each other and being located for substantial alignment with the upright walls of the stage quadrant occupying said viewing position, and curtains at said front openings controlling the view from the respective rooms of the stage set occupying said viewing position and enabling said rooms to be filled and emptied alternately in timed relation to the movement of the successive stage sets to the viewing position.

2. In a building of the character described, a stage having a substantially circular floor and upright walls dividing the same substantially into quadrants, said stage being rotatable for moving one of said quadrants to a viewing position, a pair of observation rooms facing said viewing position and extending in diverging relation away from the stage, said observation rooms having their adjacent ends spaced apart and having outer side walls extending at substantially right angles to each other, said side walls being located for substantial alignment with the upright walls of the stage quadrant occupying said viewing position, said observation rooms having front openings directed toward said viewing position and the latter being common to both rooms, and a control room serving both observation rooms and located between said adjacent ends of the observation rooms and having a transparent wall section through which said stage is visible.

3. In a building of the character described, a stage having a substantially circular floor and upright walls dividing the same substantially into quadrants, said stage being rotatable for moving one of said quadrants to a viewing position, walls defining a pair of observation rooms facing said

viewing position and extending in diverging relation away from the stage, said observation rooms having their adjacent ends spaced apart and having outer side walls extending at substantially right angles to each other, said side walls being located for substantial alignment with the upright walls of the stage quadrant occupying said viewing position, said observation rooms having front openings directed toward said viewing position and the latter being common to both rooms, a curtain for the front opening of each observation room for controlling the view of the stage therefrom, and a control room serving both observation rooms and located between said adjacent ends of the observation rooms and having a transparent wall section through which said stage is visible, said control room being defined at least in part by the walls of said observation rooms.

4. In a building of the character described, intersecting upright walls defining therebetween a substantially ninety degree display sector, other upright walls located relative to and cooperating with the first-mentioned upright walls so as to define a pair of separate observation rooms extending away from said display sector in substantially ninety degree diverging relation, a stage rotatable about an axis located substantially at the intersection of the first-mentioned upright walls and forming the floor of said display sector, portions of said first-mentioned walls extending over said stage and having their lower edges spaced thereabove, upright walls also intersecting substantially on said axis and at substantially the same angle as said first-mentioned walls and carried by said stage and adapted to be moved thereby into a position below and substantially in registration with said wall portions, the intersecting upright walls of said stage being of a height substantially equal to the spacing of said lower edges above the stage, said observation rooms having front openings facing said display sector and such that the opening of each room affords a view from such room of substantially the entire display sector, and upright front and rear walls extending between the upright walls of the adjacent sides of said observation rooms and defining therewith a control room adapted to serve both observation rooms and said display sector, said front wall being transparent and affording a view of said display sector and stage floor from said control room.

5. In a building of the character described, intersecting upright walls defining therebetween a substantially ninety degree display sector, other upright walls located relative to and cooperating with the first-mentioned upright walls so as to define a pair of separate observation rooms extending away from said display sector in substantially ninety degree diverging relation, a stage rotatable about an axis located substantially at the intersection of the first-mentioned upright walls and forming the floor of said display sector, portions of said first-mentioned walls extending over said stage and having their lower edges spaced thereabove, upright walls also intersecting substantially on said axis and at substantially the same angle as said first-mentioned walls and carried by said stage and adapted to be moved thereby into a position below and substantially in registration with said wall portions, the intersecting upright walls of said stage being of a height substantially equal to the spacing of said lower edges above the stage, said observation rooms having front openings facing said display sector and such that the opening of each room affords a view from such room

of substantially the entire display sector, and movable curtains at said front openings and controlling the view of said display sector from the respective observation rooms.

6. In a building of the character described, intersecting upright walls defining therebetween a substantially ninety degree display sector, other upright walls located relative to the first-mentioned upright walls and cooperating therewith so as to define a pair of separate observation rooms extending away from said display sector in substantially ninety degree diverging relation, tiered seats in said observation rooms, a circular floor having intersecting upright walls thereon dividing its surface into sector shaped stage areas of a size to correspond substantially with said display sector, portions of said first-mentioned walls extending over said floor and having their lower edges spaced thereabove, and means supporting said floor for rotation about an axis located substantially at the intersection of the first-mentioned upright walls such that said stage areas are adapted to be selectively brought to a position registering substantially with said display sector and in which the corresponding upright walls of the circular floor register substantially with said portions of the first-mentioned walls, said upright walls of the circular floor having a height substantially equal to the spacing of said lower edges above said circular floor, said observation rooms having front openings facing said display sector and such that the opening of each room affords a view from such room of substantially the entire display sector including the stage area in register therewith.

7. In a building of the character described, intersecting upright walls defining therebetween a display sector, other upright walls located relative to the first-mentioned upright walls and cooperating therewith so as to define a pair of separate observation rooms extending away from said dis-

play sector in diverging relation, tiered seats in said observation rooms, a circular floor having intersecting upright walls thereon dividing its surface into sector shaped stage areas of a size to correspond substantially with said display sector, portions of said first-mentioned walls extending over said floor and having their lower edges spaced thereabove, means supporting said floor for rotation about an axis located substantially at the intersection of the first-mentioned upright walls such that said stage areas are adapted to be selectively brought to a position registering substantially with said display sector and in which the corresponding upright walls of the circular floor register substantially with said portions of the first-mentioned walls, said upright walls of the circular floor having a height substantially equal to the spacing of said lower edges above said circular floor, said observation rooms having front openings facing said display sector and such that the opening of each room affords a view from such room of substantially the entire display sector including the stage area in register therewith, and movable curtains at said front openings and controlling the view of said display sector and registering stage area from the respective observation rooms.
